HANDLE

Stuart W. Parsons, New Britain, Conn., assignor
to The Stanley Works, New Britain, Conn., a
corporation of Connecticut

Application February 15, 1944, Serial No. 522,409

1 Claim. (Cl. 16—125)

The present invention relates to a handle suitable for use as a drawer pull, door pull, or the like.

The aim of the invention is to provide a handle of this sort which may be easily secured in position by means of wood screws or the like, which is neat and pleasing in appearance, which is simple and rigid in construction, which is economical in manufacture, and which, after it is secured in place, will not readily work loose or come apart.

In accordance with the present invention, I provide a bowed handle member which may be secured in place by screws passed from the front of the handle member through the same and into the panel or other member to which it is to be secured; and a cover for enclosing the handle member and concealing the securing screws from view, the handle member and the cover being so constructed and arranged that the cover may be very quickly and readily pressed into position with a wiping action and in which position it is securely held against displacement.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claim.

In the accompanying drawing, wherein is shown, for illustrative purposes, one embodiment which the present invention may take:

Figure 1 is a front view of the handle applied to a panel or the like;

Fig. 2 is a top plan view thereof;

Fig. 3 is a horizontal sectional view taken longitudinally and centrally through the handle;

Fig. 4 is a cross sectional view through one end of the handle, this view being taken substantially on line 4—4 of Fig. 3;

Fig. 5 is a cross sectional view taken through the central portion of the handle, this view being taken substantially on line 5—5 of Fig. 3; and

Fig. 6 is a perspective view of the handle as seen from the rear, a portion of the bowed handle member being broken away for the purpose of illustration.

Referring to the drawing in detail, the handle member, designated generally by the letter A, comprises a rigid strip of metal having a bowed or flattened U-shaped hand gripping portion 10 terminating in laterally extending tongues 11. The extreme ends of these tongues are turned for-

wardly, as at 12 so as to provide lips. The tongues are provided with openings 13 for accomodating the wood screws 14 by means of which the handle is secured to the front wall or panel P of a drawer or the like. This handle member is preferably formed of steel.

The cover is designated generally by the letter B and comprises a curved, channel-shaped piece of thin sheet metal which has some resiliency. 10 The cover has a central or forward wall 20 which is longitudinally curved throughout its length and which is slightly longer than the over-all length of the handle member 10. The cover has flanges 21 extending rearwardly from the upper and lower edges of the central wall and these straddle the handle member throughout its length. The rear edges of these flanges conform to the horizontal cross sectional configuration of the handle member, as will be seen most clearly from Figs. 3 to 6, 15 so that the cover will fit over the handle member and conceal the same from the front, above and below. More particularly, it will be seen that the rear edges of these flanges are curved at their central portions, as at 22, correspondingly to the curvature of the bowed portion 10 of the handle member, and the edges, to either end of the curved portions 22, are straight, as at 23. These rear edges are flush with the rear face of the handle member throughout substantially the 20 length thereof. The cover has, at the opposite ends of its forward wall 13, inturned integral lugs 24 which, as shown in Fig. 3, are adapted to take in behind the lips or outer ends 12 of the tongues whereby the cover is secured in place to the handle member.

With the arrangement described, the handle may be very quickly and readily secured in place. To do this, it is merely necessary to secure the handle member 10 (before assembling the cover thereon) to the drawer or panel P by inserting the screws from the front through the apertures 13 and then turning the screws home in the panel. The cover may then be pressed into place by positioning it over the handle member with one of the 40 lugs 24 engaging behind one of the lips 12 and the rear face of the other lug engaging the end edge of the other lip 12, and then applying pressure to successive portions of the cover so as to exert components of force towards the drawer and towards the last mentioned lug. More particularly, assuming that during the assembly of the cover on the handle member, the left hand lug 28 (referring to Fig. 3) is first engaged behind the lip, the person applying the cover may by 45 means of his thumb positioned at a press the

cover towards the handle member and towards the right hand end of the handle member, thereby bringing the flanges of the cover into contact with the edges of the handle member and then sliding his thumb in the direction of the arrow *b* without relieving the pressure. This operation will cause the cover member to elongate slightly, with the result that the right hand lug will snap in behind the right hand lip. Due to the engagement of the lugs behind the lips, the cover member is securely held in position and there is no possibility of it becoming displaced under ordinary usage.

It is further observed that my improved construction is relatively simple as it comprises but two parts each of which may be very cheaply and easily manufactured and the assembly of which may be affected with facility. The assembled handle presents a very pleasing appearance, particularly so as the handle member *A* and the securing screws are concealed from view by the cover.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claim is intended to cover all of the generic and specific features of the invention herein described and all statements of the scope of the invention which, as a matter of language, might be said to fall therebetween.

I claim as my invention:

A handle of the character described comprising a rigid handle member formed of a strip of metal and provided with a central bowed gripping portion and outwardly extending tongues at the ends of said gripping portion, said tongues having openings for accommodating attaching screws and the outer ends of said tongues being turned forwardly so as to provide lips, and a channel-shaped cover formed of resilient sheet metal and having a curved forward wall extending from one end of said handle member to the other and flanges projecting rearwardly from said forward wall and straddling said handle member, the rear edges of said flanges conforming in shape to the horizontal sectional configuration of said handle member, said forward wall of said cover having at its opposite ends preformed inwardly extending lugs engaged behind said lips, said cover being resilient in the direction of its length whereby it may be snapped into position on said handle member.

STUART W. PARSONS.
